(57) **CLAIM**

The ornamental design for a high frequency vibration relaxation device, as shown and described.

DESCRIPTION

FIG. 1 is a top perspective view of a high frequency vibration relaxation device according to a first embodiment showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view taken from circle 9 in FIG. 2;

FIG. 10 is a top perspective view of a high frequency vibration relaxation device according to a second embodiment;

FIG. 11 is a bottom perspective view of FIG. 10;

FIG. 12 is a front elevational view of FIG. 10;

FIG. 13 is a rear elevational view of FIG. 10;

FIG. 14 is a left side elevational view of FIG. 10;

FIG. 15 is a right side elevational view of FIG. 10;

FIG. 16 is a top plan view of FIG. 10;

FIG. 17 is a bottom plan view of FIG. 10; and,

FIG. 18 is a partial enlarged view taken from circle 18 in FIG. 11.

The dash-dash broken lines in the drawings illustrate portions of the high frequency vibration relaxation device that form no part of the claimed design.

The dot-dash broken lines in the drawings depict the boundaries of the partial enlarged views that form no part of the claimed design.
